UNITED STATES PATENT OFFICE

GLADEON M. BARNES, OF HASTINGS, MICHIGAN

GUN

Application filed December 10, 1929. Serial No. 413,117.

(GRANTED UNDER THE ACT OF MARCH 3, 1883, AS AMENDED APRIL 30, 1928; 370 O. G. 757)

The invention described herein may be manufactured and used by or for the Government for governmental purposes, without the payment to me of any royalty thereon.

This invention relates to a gun of the type in which the powder gases of discharge are utilized for retarding the recoil movement of the gun, and the resulting compressed gases are available for restoring the gun to battery.

The invention is characterized by the employment of a portion of the confined gases to establish a counterrecoil buffer, by an arrangement whereby the high pressure side of the mechanism is vented during a predetermined interval of counterrecoil, and by a novel provision for holding the gun in a variable position of battery at all angles of elevation.

With the foregoing and other objects in view, the invention resides in the novel arrangement and combination of parts and in the details of construction hereinafter described and claimed, it being understood that changes in the precise embodiment of the invention herein disclosed may be made within the scope of what is claimed without departing from the spirit of the invention.

A practical embodiment of the invention is illustrated in the accompanying drawings, wherein:

Figs. 1 and 1^a are longitudinal sectional views in continuation of each other of a gun constructed in accordance with the invention and showing the parts in position of in battery;

Fig. 2 is a view similar to Fig. 1 and showing the parts in position of full recoil;

Figs. 3 and 4 are respectively in plan view and a view in longitudinal section of the cradle;

Fig. 5 is a view in side elevation with parts in section of the recoil and counterrecoil cylinder;

Fig. 6 is a longitudinal sectional view of the cradle showing the moving parts in the position they occupy at the conclusion of the initial half of counterrecoil;

Fig. 7 is a view on the line A—A of Fig. 1^a;

Fig. 8 is a view on the line B—B of Fig. 1^a;

Fig. 9 is a view on the line C—C of Fig. 1^a;

Fig. 10 is a view on the line D—D of Fig. 1;

Fig. 11 is a view on the line E—E of Fig. 1;

Fig. 12 is a view on the line F—F of Fig. 1;

Fig. 13 is a view on the line G—G of Fig. 1;

Fig. 14 is a view on the line H—H of Fig. 11;

Fig. 15 is a view on the line J—J of Fig. 12;

Figs. 16 and 17 are respectively views in side elevation and bottom plan of the actuating rod;

Fig. 18 is a detail view in rear elevation of one of the guides for the actuating rod;

Fig. 19 shows detail views of the plunger engageable with the actuating rod; and

Fig. 20 is a detail sectional view on the line K—K of Fig. 6.

Referring to the drawings by numerals of reference:

In Figs. 1, 1^a, and 11 there is shown a channel-shaped cradle 5 provided with trunnions 6 and having guideways 7 on the upper marginal portions of its side plates 5^a for receiving the slides 8 on the jacket 9 of a gun barrel 10. A recoil and counterrecoil cylinder 11 positioned underneath and parallel to the gun is provided with a pair of annular hangers 12—12 which embrace the gun and are secured thereto in a substantially similar manner, being confined between a shoulder 13 of the gun and a collar 14 threaded on the gun. The hangers 12 are provided with slides 15 receivable in the guideways 7 to prevent rotational displacement of the cylinder during reciprocation and the rear hanger is interlocked with the jacket 9 through the key 9^a.

The rear cylinder head 16 is formed with a transversely apertured lug 17 whereby the cylinder is connected to the gun lugs 18 through a pin 19.

Referring to Figs. 10, 11 and 14, the interior of the cylinder 11 is in communication

70

80

85

90

100

with the interior of each hanger 12 through offset passages 20 and 21 connected by a longitudinally extending passage 22 in which is placed a poppet valve 23 normally held open by a spring 24. The inlet passage 20 leading into the hanger is in alignment with an outlet passage 25 in the wall of the gun, thereby permitting the rapidly expanding gases of discharge to be conducted from the bore 10 of the gun to the cylinder.

While only one set of the gas passages 20-21-22, namely, that one associated with the rear hanger, is required for the normal successful functioning of the gun illustrated, it may be necessary or advisable under certain conditions of bore pressure, weight of the recoiling parts of a gun and the length of recoil thereof, to provide for variations in the volume of gases to be admitted into 20 the cylinder. To this end a valve 20^a (Fig. 5) is indicated in the passage 20 in the forward hanger and in the subsequent description this valve will be considered as being closed.

25 Within the cylinder 11 is a hollow piston rod 26 secured to the front plate 27 of the cradle (Fig. 1^a) and having its piston head 28, spaced from the cylinder head 16 to constitute a buffer chamber 29. The wall of the 30 piston rod is provided with apertures 30, and a valve 31 in the piston head 28 enables the gases to pass into the buffer chamber 29. An adjustable relief valve 32 is placed in the wall of the cylinder to allow the gases in 35 the buffer chamber to slowly escape.

Extending rearwardly from the piston head 28 is a sleeve 33 whose outer wall contains a number of packing rings 34. Upon 40 relative movement of the piston and cylinder, the sleeve functions to close the gas passage 21 (which is located on the line 12-12 of Fig. 1) in the cylinder until the pressure in the buffer chamber has been developed sufficiently to insure the closing of the poppet valve 23 during the remainder of the recoil stroke and the initial counterrecoil 45 stroke.

50 Mounted on the forward extremity of the hollow piston rod 26 (Fig. 1^a) is a sleeve valve 35 normally held in a forward position by a spring 36 (Fig. 3) to cover outlet ports 37 in the piston. The actuating mechanism for 55 retracting the sleeve valve consists of a driving rod 38 and a pivoted lever 39, both mounted on the cradle (Figs. 4 and 8) and the latter having a slot 40 which receives a pin 41 on an arm 42 of the valve. In the normal closed position of the valve, the lever is held in a vertical position with the pin 41 in engagement with the forward end of the slot by 60 means of a plunger 43 mounted on the floor of the cradle. In this position the upper end of the lever is disposed in a recess 44 in the rod which is being held in retracted position by spring 45, the rear end of the rod

engaging a buffer 46 carried in a bracket 47.

The actuating mechanism for moving the rod against the action of its spring comprises a plunger 48 carried in a housing 49 secured to the cylinder 11 (Figs. 3 and 10). When the cylinder is at the end of its recoil stroke, the plunger extending through a slot 50 in a guide bracket 51 (Figs. 12 and 18) engages in one of a set of teeth 52 formed on the rear extremity of the driving rod 38 so that as 75 the cylinder begins to counterrecoil the rod is moved forward to the position shown in Fig. 6.

During the forward movement of the rod it actuates the lever 39 to retract the sleeve valve 35 and when the forward movement of the rod has been discontinued, as will presently be described, a recess or notch 53 in the rod enables the valve spring 36 to restore the lever to the vertical position. On counter 85 movement of the rod, the lever 39 will be rotated in the opposite direction but the provision of the slot 40 therein will prevent it from actuating the sleeve valve.

The interval during which the sleeve valve 90 35 is to uncover the outlet ports 37 of the piston rod is predetermined and is controlled by disconnecting the plunger 48 from the rod 38 at a definite point in the counterrecoil stroke of the cylinder. This is accomplished 95 by rotating the rod and to this end cam grooves 54 (Figs. 4 and 9) formed in the rod receive pins 55 mounted in opposite sides of a bearing 56 secured to the cradle. In the present instance this disconnection is effected 100 approximately in the middle of the stroke. A portion of the rod 38 at one side of the teeth is cut away as at 57 so that when the rod has been rotated the plunger will be free to continue its forward movement with 105 the cylinder 11 and will be carried clear of all teeth on the rod before counter rotation of the rod on the return stroke thereof has placed the teeth in their original position.

Because the structure of the cylinder and 110 piston are not such as to retain the gases indefinitely, it becomes necessary to provide some means for holding the gun in battery irrespective of its inclination. A provision for accomplishing this object is illustrated in 115 Figs. 1 and 2 and consists of a piston 58 mounted in a housing 59 and secured centrally to the under side of the cradle and normally maintained in the forward position by a spring 60 having a sufficient capacity to support the gun in all positions of elevation. The piston is connected to the recoil cylinder by means of a gun holding arm in the form of a pawl 61, pivotally mounted at the rear of the piston and arranged to engage in teeth 62 125 formed in the under side of the rear cylinder head 16. The pawl is normally held in the elevated tooth-engaging position by a plunger 63 and is adapted to be rotated on rearward movement by riding on a cam surface 64 130

formed in the housing. A catch 65 is carried in the rear portion of the housing 59 in line with and immediately in rear of the hooked tail end 66 of the pawl 61. The catch is secured to a transversely disposed yoke 67 (Fig. 13) in whose ends are fixed trip rods 68 extending through the housing into the path of lugs 69 (Figs. 1, 2 and 5) on the under side of the cylinder 11.

When the cylinder commences its rearward movement on recoil it is locked to the piston and carries it along until the tail end 66 of the pawl depresses the catch 65 and riding on the cam surface 64 is rotated thereby to disengage it from the tooth 62 of the cylinder. The tail end 66 of the pawl is then engaged by the catch 65 which is free to rise and it is thus held until all of the teeth on the cylinder have passed beyond the pawl. The lugs 69 striking the strip rods 68 depress the catch and release the pawl and its piston 58 which moves forward under the influence of the piston spring 60. As the cylinder returns to battery, the pawl re-engages one of the teeth to securely hold the cylinder and the gun at all angles of elevation.

In operation, when the gun is fired, a portion of the rapidly expanding gases of discharge will be delivered through the passages 20, 22, 21 to the cylinder 11 which by reason of its attachment to the gun is partaking of the recoil movement. During the initial stage of recoil the pressure in the cylinder exceeds the rapidly decreasing pressure in the bore of the gun and effects the closing of the poppet valve 23. Thereafter the gases which are confined in the cylinder will be compressed as the forward end of the cylinder approaches the piston head 28 and will act to yieldingly check the recoil of the gun. The compressed gases in the forward or high pressure side of the cylinder will be delivered at a rate controlled by the valve 31 to the buffer chamber 29 or low pressure side of the cylinder. During the interval required to develop sufficient pressure in the buffer chamber to insure the closing of the poppet valve 23 against any pressure which still exists in the bore of the gun, the gas inlet passage 21 of the cylinder is blocked off by the sleeve 33 on the piston head.

The controlled delivery of gases to the buffer chamber 29 and the gradual exhausting of this chamber through the valve 32 maintain the chamber at a low pressure and enable the higher compressed gases in the forward part of the cylinder to restore the gun to battery. In order that the counterrecoil stroke may not be too violent the gases in the high pressure side of the cylinder are permitted to escape through the ports 37 during the first half of the stroke, these ports being uncovered by the valve 35 which is moved through the rod 38 and lever 39, as previously outlined. The ports are then closed and during the final half

of the stroke, the piston compresses the gases in the buffer chamber and establishes such an equalization of pressures on either side thereof as will enable the gun to be eased into battery. At the end of counterrecoil all the gases escape from the cylinder.

The operation of the means for releasably holding the gun in battery is apparent from the description. The mechanism is designed to function at variable positions of in battery and for variable lengths of recoil.

The gas operation of the recoil and counterrecoil arrangement may apply to a gun independently of each other or with other types of complementary mechanisms. If the gases are wanted primarily to check counterrecoil, the compression chamber may serve as a storage reservoir or a small part of the gases may be afforded delayed admission directly to the buffer chamber.

I claim:

1. In a gun, a cradle, a barrel reciprocally mounted in the cradle, a cylinder within the cradle and fixed to the barrel, a piston in the cylinder defining a compression and a buffer chamber and having a hollow piston rod fixed to the cradle, a passage establishing communication between the compression chamber of the cylinder and the bore of the barrel, a normally open valve in said passage, a valve in the piston establishing communication between the chambers, means on the piston for closing the passage from the barrel until a predetermined pressure is developed in the buffer chamber, a relief valve for the buffer chamber, a relief valve for the compression chamber, means for opening said compression chamber relief valve during the initial half of the counterrecoil stroke of the cylinder and means for releasably holding the barrel and cylinder assembly in battery.

2. In a gun, a cradle, a barrel reciprocally mounted in the cradle, a cylinder fixed to the barrel, a piston in the cylinder defining a compression and a buffer chamber and having a hollow piston rod fixed to the cradle, a passage establishing communication between the compression chamber of the cylinder and the bore of the barrel, a normally open valve in said passage, a valve in the piston establishing communication between the chambers, means on the piston for closing the passage from the barrel during an intermediate portion of the stroke of the cylinder, a relief valve for the buffer chamber, a relief valve for the compression chamber, means for opening said compression chamber relief valve during the initial half of the counterrecoil stroke of the cylinder and means for releasably holding the barrel and cylinder assembly in battery.

3. In a gun, a cradle, a barrel reciprocally mounted in the cradle, a cylinder fixed to the barrel, a piston in the cylinder defining a com-

pression and a buffer chamber and having a hollow piston rod fixed to the cradle, a passage establishing communication between the compression chamber of the cylinder and the bore of the barrel, a normally open valve in said passage, a valve in the piston establishing communication between the chambers, a relief valve for the buffer chamber, a relief valve for the compression chamber, means for opening said compression chamber relief valve during the initial half of the counterrecoil stroke of the cylinder and means for releasably holding the barrel and cylinder assembly in battery.

4. In a gun, a cradle, a barrel reciprocally mounted in the cradle, a cylinder fixed to the barrel, a piston in the cylinder defining a compression and a buffer chamber and having a hollow piston rod fixed to the cradle, a passage establishing communication between the compression chamber of the cylinder and the bore of the barrel, a normally open valve in said passage, a valve in the piston establishing communication between the chambers, a relief valve for the buffer chamber, a relief valve for the compression chamber, and means for releasably holding the barrel and cylinder assembly in battery.

5. In a reciprocating gun, a recoil mechanism utilizing the compressive action and reaction of the gases of discharge to check recoil and restore the gun to battery, means for relieving the pressure of the gases during the initial half of the counterrecoil stroke of the gun and a counterrecoil mechanism employing the elements of the recoil mechanism and gases from the recoil mechanism.

6. In a reciprocating gun, a recoil mechanism utilizing the compressive action and reaction of the gases of discharge to check recoil and restore the gun to battery, means for relieving the pressure of the gases during the initial half of the counterrecoil stroke of the gun and a counterrecoil mechanism employing the gases from the recoil mechanism.

7. In a reciprocating gun, a recoil mechanism utilizing the compressive action and reaction of the gases of discharge to check recoil and restore the gun to battery and a counterrecoil buffer mechanism employing the elements of the recoil mechanism and gases from the recoil mechanism.

8. A cradle, a gun reciprocally mounted thereon, a cylinder moving with the gun, a piston in the cylinder having a hollow piston rod fixed to the cradle, a passage establishing communication between the cylinder and the bore of the barrel and positioned to be closed by the piston after initial recoil movement of the cylinder, a relief valve at the forward end of the hollow piston rod, an actuating mechanism for said valve carried by the cradle and including a spring held rod, driving means on the cylinder for picking up said

rod at the commencement of counterrecoil, means for subsequently rotating the rod to disengage it from the driving means.

9. A cradle, a gun reciprocally mounted thereon, a cylinder moving with the gun, a piston in the cylinder having a hollow piston rod fixed to the cradle, a passage establishing communication between the cylinder and the bore of the barrel, a relief valve at the forward end of the hollow piston rod, an actuating mechanism for said valve carried by the cradle and including a spring held rod, driving means on the cylinder for picking up said rod at the commencement of counterrecoil, means for subsequently rotating the rod to disengage it from the driving means.

10. A cradle, a gun reciprocally mounted thereon, a cylinder moving with the gun, a piston in the cylinder having a hollow piston rod fixed to the cradle, a passage establishing communication between the cylinder and the bore of the barrel, a relief valve at the forward end of the hollow piston rod and means for opening said relief valve during the initial half of the counterrecoil stroke of the cylinder.

11. A cradle, a gun reciprocally mounted thereon, a cylinder moving with the gun, a piston in the cylinder having a hollow piston rod fixed to the cradle, a passage establishing communication between the cylinder and the bore of the barrel, a relief valve at the forward end of the hollow piston rod and means for opening said relief valve during the counterrecoil stroke of the cylinder.

12. A cradle, a gun reciprocally mounted thereon, a recoil mechanism utilizing the compressive action and reaction of the gases of discharge to check recoil and restore the gun to battery, and means controlled by movement of the gun for rapidly relieving the pressure of the gases during a part of the counterrecoil stroke of the gun.

13. A cradle, a gun reciprocally mounted thereon, a cylinder moving with the gun, a fixed piston working in the cylinder and defining therewith a buffer chamber, means for admitting gases of discharge of the gun into the buffer chamber for compression on the counterrecoil stroke of the cylinder.

14. A cradle, a gun reciprocally mounted thereon, a counterrecoil mechanism including a buffer chamber, means for admitting gases of discharge of the gun during the recoil stroke of the gun into the buffer chamber for compression on the counterrecoil stroke of the gun.

15. A cradle, a gun reciprocally mounted thereon, a counterrecoil mechanism including a buffer chamber, means for admitting gases of discharge of the gun into the buffer chamber for compression on the counterrecoil stroke of the gun.

16. A cradle, a recoil gun mounted thereon, means for checking the gun in recoil and

restoring it to battery, a gun-holding member carried by the cradle, a movable gun-engaging element on said member, means for disengaging said element from the gun re-
5 coil movement of the gun, means for holding the element disengaged and means for inoperating the holding means.

17. In a gun structure a channel-shaped cradle having guideways on its side plates, 10 a gun slidably supported in the guideways and a cylinder underneath the gun having hangers embracing the gun and slidably sup-
ported in the guideways.

CERTIFICATE OF CORRECTION.

Patent No. 1,808,097.

Granted June 2, 1931, to

GLADEON M. BARNES.

It is hereby certified that error appears in the printed specification of the above numbered patent requiring correction as follows: Page 4, after line 128, insert the following as claim 16:-

16. A cradle, a recoil gun mounted thereon, means for checking the gun in recoil and restoring it to battery, a gun holding piston carried by the cradle, a pawl on one end of the piston, means for normally holding the pawl in gun-engaging position, a fixed cam operating on recoil of the gun to move the pawl out of engagement with the gun, a catch for holding the pawl disengaged, a trip member for the catch and means on the guns for striking the trip member.;
page 5, line 4, claim 16, appearing in patent, after "gun" insert the word during; the claims now appearing in the patent as numbers 16 and 17 should bear numbers respectively 17 and 18; and that the said Letters Patent should be read with these corrections therein that the same may conform to the record of the case in the Patent Office.

Signed and sealed this 4th day of August, A. D. 1931.

Wm. A. Kinnan,
Acting Commissioner of Patents.
